P. IRWIN.

DEVICE FOR MANUFACTURING VACUUM CONTAINERS.
APPLICATION FILED SEPT. 15, 1915.

1,284,194.

Patented Nov. 5, 1918.

Payson Irwin, Inventor
By his Attorneys
W. Astick & F. L. Flocke

UNITED STATES PATENT OFFICE.

PAYSON IRWIN, OF STAMFORD, CONNECTICUT.

DEVICE FOR MANUFACTURING VACUUM-CONTAINERS.

1,284,194.

Specification of Letters Patent.

Patented Nov. 5, 1918.

Application filed September 15, 1915. Serial No. 50,917.

To all whom it may concern:

Be it known that I, PAYSON IRWIN, a citizen of the United States of America, residing at Stamford, Fairfield county, Connecticut, ⁵ cut, have invented certain new and useful Improvements in Devices for Manufacturing Vacuum-Containers, of which the following is a specification.

My invention relates to devices for manufacturing vacuum containers and the object ¹⁰ of the invention is to produce a device of the character set forth whereby a vacuum container may be easily, cheaply and effectively made.

Although the principles of the invention ¹⁵ may be adapted to the manufacture of any desired form of vacuum container, I have chosen to illustrate the working of a form of apparatus embodying my invention in connection with the type of vessel described and claimed in my application for patent on vacuum containers filed September 15, 1915, Serial No. 50,916.

In the following is described, in connection ²⁵ with the accompanying drawings, a form of apparatus illustrating one way of carrying out my invention, the features thereof being hereinafter more particularly pointed out in the claims.

In the drawings Figure 1 is a longitudinal vertical, sectional view of said form of apparatus along the line 1—1 of Fig. 2 showing in full lines the two parts of the container before they have been brought together and ³⁵ in dotted lines said two parts after they have been brought together; Fig. 2 is a front view of said apparatus; Fig. 3 is a cross-sectional view of the parts shown in Fig. 1 along the line 3—3 and Fig. 4 is a vertical sectional view of the completed container.

Similar letters of reference indicate similar parts throughout the several views.

A indicates a shell carried by legs or ⁴⁵ standards B, B and connected with a vacuum pump (not shown) by a pipe C controlled by a two-way valve D adapted to connect with the vacuum pump or to relieve the vacuum through pipe E as the case may be. The shell A is provided with a door F swinging on hinge G and adapted to be secured to the shell by screw clamps H, H. A gasket I provides an air-tight closure of the door and shell. The central portion of door F is ⁵⁵ provided with a flexible diaphragm J of material impervious to air such as rubber or

spring steel. The diaphragm J is shown as held in the door by screw ring K. Diaphragm J carries a stem L seated in socket M on the outside and a flat plate N of any suitable material on the inside thereof. Stem L projects outwardly through cross bar O in which it may be held by jaws P, P, taking into a slot (not shown) in the stem. Cross bar O may be mounted on door F in any convenient way as by rods Q, Q. R is a mandrel centrally supported in shell A. S is a saddle mounted on the floor of shell A. T is the inner container of the vacuum container, shown as mounted on mandrel R, and U is ⁶⁵ the outer container thereof shown as carried by saddle S.

The operation of the device is as follows: The door being open the inner container T is slid onto the mandrel and the outer container ⁷⁰ U is placed upon the saddle leaving a space between the upper edges of the respective containers, as shown in Fig. 1. The bottom of container U should be substantially in contact with diaphragm J when the door is ⁷⁵ closed and stem L held by jaws P, P. As illustrated outer container T is provided with a rim V having a flat surface beneath, and a shoulder W over which the upper end of container U is adapted to slide, as herein-after described, until its upper flat edge contacts with the lower flat surface of rim V on container T. X is a lug on the bottom of container U adapted to contact with the bottom of container T when the parts are ⁸⁵ locked together.

The containers being in position, the door is closed and clamped to the shell with the central portion of the diaphragm substantially in contact with the bottom of container U, the stem L being held against inward movement by jaws P, P. The shell is then evacuated. When the evacuation is completed to the desired degree the jaws P, P are released from stem L and the atmospheric pressure drives the diaphragm and container U inwardly until the upper flat edge of said container contacts with the under flat surface of rim V on the outer container and lug X rests against the bottom ⁹⁵ 100 of container T. The vacuum is then released, the door opened and the vacuum container removed, the atmospheric pressure holding the two containers together with the evacuated space between them.

If desired any suitable cementitious substance may be placed on the under flat sur-

face of rim V and on shoulder W to assist in holding the containers together and forming an air-tight connection.

The container may be made of any suitable material substantially impervious to air such as glass, metal, treated paper, etc., and may be of any suitable form. The shell may of course be adapted to contain one or any desirable number of containers at a time.

As it is obvious that the details of construction may be greatly varied without departing from the general principles of the invention, I do not restrict myself to such details further than the scope of the appended claims demands.

I claim:

1. In a device for manufacturing vacuum containers, an air-tight chamber, a support 20 therein for an inner container, a support for an outer container, a flexible diaphragm adapted to respond horizontally to atmospheric pressure when the vacuum is established and means for evacuating said chamber.
2. In a device for manufacturing vacuum containers, an air-tight chamber, a mandrel supported within the same in a horizontal position and distant from the walls of the chamber, a saddle on the floor of said chamber adjacent said mandrel and adapted to support a suitable body surrounding said mandrel and flexible means at the end of the chamber opposite the mandrel support adapted to be flexed toward the free end of the mandrel by atmospheric pressure.
3. In a device for manufacturing vacuum containers, an air-tight chamber, supports within the same for the articles to be operated upon, a door at one end of said chamber, a flexible diaphragm in said door, means for restraining said diaphragm from inward horizontal collapse and releasing means freeing said diaphragm for collapse caused by atmospheric pressure.
4. In a device for manufacturing vacuum containers, an air-tight chamber, evacuating means therefor, means for relieving the vacuum, a mandrel within the chamber 50 adapted to support the inner container of a vacuum container in horizontal position, a saddle within the chamber adapted to support the outer container of a vacuum container in a position surrounding the mandrel and the inner container, a flexible wall in the chamber adjacent the free end of the

mandrel, means for holding said flexible wall against collapse when the chamber is being evacuated and releasing means for said last-named means so that said flexible wall may be collapsed horizontally inward by atmospheric pressure.

5. In a device for manufacturing vacuum containers, an air-tight chamber, means for evacuating the same and for relieving the vacuum, supports within the chamber for the coöperating inner and outer containers of a vacuum container adapted to hold the same in a horizontal position and means responding to atmospheric pressure for causing relative horizontal movement between said inner and outer containers while said chamber is in an evacuated condition.

6. In a device for manufacturing vacuum containers, an air-tight chamber, a support 75 for an inner container, a support for an outer container, means for evacuating the chamber and means actuated by atmospheric pressure for bringing the parts of the container together while maintaining so the vacuum.

7. In a device for manufacturing vacuum containers, an air-tight chamber, means for positioning the container parts therein relative to each other but out of contact with 85 each other, a flexible diaphragm adapted to respond to atmospheric pressure to bring said container parts into contact and means for evacuating said chamber.

8. In a device for manufacturing vacuum 90 containers, an air-tight chamber, independent supports for the container parts, means adapted to respond to atmospheric pressure to bring said parts into contact when the vacuum is established and means for evacuating the chamber.

9. In a device for manufacturing vacuum containers, an air-tight chamber, means for positioning the container parts therein out of contact with each other and movable relatively toward each other, means adapted to 100 respond to atmospheric pressure to bring said parts into contact when the vacuum is established and means for evacuating the chamber.

In testimony whereof I have signed this specification in the presence of two subscribing witnesses.

PAYSON IRWIN.
